SHELF

Carl A. Johns, Chicago, Ill.

Application November 28, 1934, Serial No. 755,134

4 Claims. (Cl. 211—93)

My invention relates to shelves and particularly to kitchen shelves adapted to serve as repositories for pot covers and the like.

It is an object of my invention to provide a shelf 5 of the type described which will be simple and inexpensive to make and which can be sold at a low price. Another object is to provide a shelf which will be collapsible so that it can be shipped in compact form but which will be easy to assemble into operative position. Other and more detailed objects will become apparent as the description of my invention proceeds.

Reference will now be had to the drawing which shows a specific embodiment of my invention together with certain alternative hook mechanisms and in which:

Figure 1 is a perspective view of my shelf in assembled condition;

Figure 2 is a side view corresponding to Figure 1;

Figure 3 is a front elevation of the hook of Figures 1 and 2 shown in the position which it takes when the shelf is in collapsed condition;

Figure 4 is a front elevation of an alternative hook;

Figure 5 is a partial side view corresponding to Figure 2 but showing still another alternative hook mechanism; and

Figure 6 is a partial top view showing the latching device used with the hook of Figure 5.

Turning now to the drawing in more detail, it will be seen that my shelf comprises a back member 11 and a front member 12 fastened together at their lower edges by any suitable means, e. g. 35 by means of staples 13. I prefer to make members 11 and 12 of cardboard or, still better, of boxboard, since this gives a light, inexpensive, yet strong construction. Member 11 may suitably be boxboard .100 inch thick and member 12 may 40 suitably be boxboard .080 inch thick. The dimensions may be varied within wide limits but, member 11 may, for instance, be 20 inches long and 10 inches high.

Member 11 is provided with two or more eyelets 14 near its upper edge to receive hooks or nails to fasten the shelf to a wall or door.

Member 12 is scored along the line 15 so as to fold fairly readily. When the shelf is shipped and sold it is in collapsed condition. Member 12 50 is then alongside member 11 and must be folded outward when put in assembled condition. Member 12 is preferably somewhat less high than member 11 so that its top edge is below the top edge of member 11 when the two are folded together.

Near the ends of member 11 and at a level

slightly below the level of the upper edge of member 12 when the latter is folded alongside member 11 are located a pair of ring plates 16 which may suitably be fastened to member 11 by means of rivets 17.

These ring plates carry hooks which are preferably of the form shown in Figures 1, 2 and particularly 3. These hooks are mounted to swing horizontally rather than vertically since to swing them out from a vertical position would involve 10 bending and thereby weakening member 12 to an otherwise unnecessary extent. When member 12 is folded alongside member 11 the hooks are swung inward horizontally and are held between members 11 and 12.

These hooks are made from a piece of spring wire 18 bent into the shape shown in Figure 3. The hooks carry outer projections 19 and inner projections 20 as shown. The hooks are adapted to cooperate with eyelets 21 located near the upper corners of member 12.

To assemble my shelf, member 12 is folded outward along scored line 15 and the hooks are swung outward. The two legs of the hook shown in Figure 3 are then squeezed together which permits projections 19 to pass through eyelets 21 and member 12 is thus held between projections 19 and projections 20. The lower leg of the hook shown in Figure 3 is shorter than the upper leg and the projections are preferably bent as shown 30 to parallel member 12 when the shelf is assembled.

The angle between members 11 and 12 when the shelf is assembled may suitably be from 15° to 45° and preferably about 30°. The shelf in assembled condition may be described as trough-like.

Figure 4 shows an alternative form of hook which may be fastened to member 11 at 22. Curved part 23 slips around the edge of member 12 and through eyelet 21 and member 12 is then held between part 23 and projection 24.

Figures 5 and 6 show still another form of hook consisting of a bent wire 25 fastened to member 11 by ring plates 16 and latching onto member 12 by means of latch 26 having a projection 27 to hold the end of the hook. Latches 26 are provided at each end of member 12, facing inward so that the covers contained in the shelf will not disengage the hook.

When my shelf is mounted on a wall it is desirable to place a piece of wood 28 back of it. This can be used to support a row of hooks 29 on which various kitchen utensils can be hung.

While I have described my invention in connection with certain specific embodiments thereof

it is to be understood that I do not wish to be limited thereby and that various modifications falling within the scope of the appended claims will occur to those skilled in the art.

5 1 claim:

1. A collapsible kitchen shelf comprising a vertical back member, means for attaching said back member to a vertical surface, a front member attached to said back member at the respective 10 lower edges of the two members, said front member being adapted to lie alongside said back member when said shelf is in condition for shipping and to fold forward to form a trough-shaped shelf, a pair of hooks pivotally attached to said 15 back member and adapted to swing inward and be confined between said two members when said shelf is in condition for shipping and to swing outward for attachment to said front member when said shelf is in condition for use, and means 20 for removably attaching said hooks to said front member, each hook including a pair of substantially parallel legs, the free ends of which are adapted to engage means on said front member to hold said front member in rigid position.
- 25 2. A collapsible kitchen shelf for pot covers or the like comprising a vertical boxboard back member, means located near the upper edge of said member for attaching said member to a wall, a front boxboard member of substantially 30 the same length as said back member and of substantially lesser height than said back member attached to said back member along the lower edges of said two members, said front member being scored along a horizontal line immediately 35 above the points of attachment to said back member to enable said front member to lie alongside said back member when said shelf is in condition for shipping and to fold forward to form a trough-shaped shelf, a pair of hooks permanently attached to said back member at the ends thereof 40 at a level immediately below the upper edge of

said front member when said front member is alongside said back member, said hooks being adapted to swing inward horizontally and to be confined between said two members when said shelf is in shipping condition and to swing outward to permit their attachment to said front member when said front member is in position to form a trough-shaped shelf, means carried by said front member near the upper corners thereof for receiving said hooks, and projections on said hooks to prevent either forward or backward movement of said front member when said hooks are positioned in said last-mentioned means.

5 10 15 3. A shelf according to claim 2 in which each of said hooks includes a pair of substantially parallel legs, the free ends of which are adapted to engage said means for receiving said hooks.

4. A collapsible kitchen shelf comprising a vertical back member, means for attaching said back member to a vertical surface, a front member attached to said back member at the respective lower edges of the two members, said front member being adapted to lie alongside said back member when said shelf is in condition for shipping and to fold forward to form a trough-shaped shelf, a pair of hooks pivotally attached to said back member and adapted to swing inward substantially horizontally and be confined between said two members when said shelf is in condition for shipping and to swing outward for attachment to said front member when said shelf is in condition for use, means carried by said front member for receiving said hooks, means carried by each of said hooks adapted to project through said last-mentioned means and to prevent forward motion of said front member when said shelf is in condition for use and additional means carried by each of said hooks adapted to prevent rearward motion of said front member when said shelf is in condition for use.

35 40 CARL A. JOHNS.
